UNITED STATES PATENT OFFICE

2,648,632

VARIABLE DETENTION LIQUID TREATING APPARATUS

Walter J. Hughes, Chicago, Ill., assignor to Infilco Incorporated, Chicago, Ill., a corporation of Delaware

Application August 13, 1947, Serial No. 768,307

6 Claims. (Cl. 210—16)

1

This invention relates to an apparatus and method for treating liquid by what is known as the "slurry process."

The apparatus and process of my invention can be applied to different phases of liquid treatment. It can, for example, as shown in Figures 1 to 3, be used for the flocculation, or coagulation, processes in which water is subjected to gentle agitation to flocculate solids therein. It can also be used, as shown in Figures 4 to 9, as a complete slurry type treating unit in which the solids formed in the treatment process are separated from the fluid medium.

One object of my invention is to provide an apparatus in which, and a process by which, the minimum detention time, as well as the average detention time, of liquid undergoing treatment can be accurately controlled, thus providing more efficient utilization of the volume of the treating basin.

Another object of my invention is to provide an apparatus which completely eliminates the danger of short circuiting of liquid undergoing treatment in the mixing zone in a slurry process in which the liquid, on an average, is recirculated many times.

Another object of my invention is to more accurately control the detention time of liquid undergoing treatment in a slurry treating process of the type described in my patents, Nos. 2,245,587 and 2,245,588.

A further object of this invention is to provide a slurry treating apparatus adapted for rectangular basins and which accurately proportions the recirculation as desired, and eliminates short circuiting of liquid undergoing treatment in the mixing zone.

A still further object of my invention is to provide a slurry treating process and apparatus wherein the relative volume of the flows from the mixing zone to the clarification zone and the recirculation within the mixing zone may be separately and accurately controlled in order to adapt the slurry treating process to relatively large rectangular basins.

A still further object of my invention is to provide a flocculation, or coagulation, apparatus in which the amount and time of recirculation can be adjusted over a fairly wide range of values and in which short circuiting is minimized.

A still further object of this invention is to provide a more thorough and rapid mixing of liquid and reagent in a mixing chamber, while avoiding high velocities and turbulence.

These and other objects of my invention will be

2

apparent from the description and claims which follow.

Apparatus of the type described in my patents mentioned above has found wide acceptance in industrial and municipal treatment of water and other liquids. However, such apparatus heretofore has been restricted practically to either round or square treating basins of considerable depth. In such equipment, as is well known, the liquid undergoing treatment is, on the average, recirculated in the mixing zone a number of times and then passed into an intermediate level of a relatively quiescent clarification zone, an output quantity of water escaping from the slurry into a body of clear water in an upper part of the basin and the greater portion thereof being returned to the mixing zone for further treatment. For example, it is common to design this type of apparatus to provide about ten minutes detention time within the mixing zone and to turn over the contents thereof at least once each minute, and to design the slurry flow passages and slurry holding space of the clarification zone so as to provide for complete recirculation in about five minutes, the amount of slurry so recirculated usually being about twice the output of treated water. Such detention times are necessary in order to hold short circuiting to a minimum.

I have found it advantageous to use a pressure chamber between the mixing zone and the slurry holding space so that the circulating slurry can be distributed uniformly throughout the length of an elongated treating basin. My discovery, however, goes beyond a mere pressure chamber as I have found that detention time can be reduced if the apparatus is designed so as to minimize short circuiting through the apparatus. I have also found that it is possible to design apparatus to provide for proper treatment of a variable water supply. In the past it was necessary to construct such equipment so as to provide a detention and rate of circulation sufficiently high to overcome the defects caused by short circuiting at the worst operating condition and to overtreat at all other times. I eliminate the possibility of short circuiting in the mixing zone, and thereby am enabled to reduce my total detention time; and also provide means whereby the detention time in the mixing zone can be varied over a wide range to fit variable conditions. The latter element is quite important, for in many installations the nature of the liquid varies in a manner which makes changes in detention in the treating chamber very desirable, and in those cases

55

the detention time can be adjusted to meet such conditions. Such adjustment of the detention time not only permits use of smaller basins but makes operating more efficient.

I have found that the factor of primary importance in determining the efficiency of the slurry type apparatus is the control of the minimum detention time, or, what means the same thing, the control of short circuiting, and especially in the mixing zone. To illustrate, assume that satisfactory results can be secured by five minutes detention in the mixing or reaction zone, but that it is possible for liquid to go through the zone and escape as partly treated water in less than a minute, and that a sufficiently large amount of liquid will short circuit, when operating with five minutes detention, to upset operating conditions at times. In such a case it may be necessary to enlarge the treating apparatus, and all the parts thereof, so as to provide a minimum detention of ten minutes and elongate the passageway from the mixing chamber to the clarification chamber so as to make the minimum time two minutes, or slow down the rate of throughput. Heretofore such equipment has been designed to provide an average detention time larger than necessary in order to control short circuiting within reasonable limits. The apparatus and process of my invention are directed to the eliminating of short circuiting in the reaction zone and to making the total minimum and maximum detention times closer to the total average detention time.

One advantage of my invention, when applied to slurry type treating plants, is in the fact that it is primarily designed for use in rather large rectangular basins, which is desirable in large installations. I am also able to control flows through all portions of such basins so that each part of the apparatus is operating at maximum efficiency. It is obvious that in apparatus of this type, in which the entire reaction is compressed into a relatively short period, it is extremely important to control flow characteristics in all portions of the apparatus, as permissible output is fixed by the rate at which treatment takes place at the most inefficient point.

Another important advantage of my invention resides in the fact that it provides very thorough mixing of the liquid being treated, the treating reagent, and slurry in the slurry process, in a very short time and without using a high velocity flow or turbulent agitation. One of the essential requirements of efficient operation of a slurry type liquid treating plant is the rapid and thorough mixing of slurry, liquid to be treated and reagent, as the reaction between the treating reagent and the precipitable solids in the water must take place in the presence of slurry particles. In my invention the water to be treated is introduced into one end of the mixing chamber, preferably tangentially to a rolling cylindrical body of slurry, and additional slurry is tangentially discharged at the surface of the rolling body of slurry throughout the length of the mixing chamber so that the entering liquid is thoroughly mixed with the slurry by the time it reaches the other end of the mixing chamber.

When considered as a slurry type liquid treating apparatus, my invention comprises a relatively long rectangular treating basin with an elongated hood in the lower part thereof. The inlet for liquid to be treated and the liquid moving member are at opposite ends in smaller equipment, while in large sizes I utilize two im-

pellers, one at each end of the apparatus, and deliver the liquid into the center, thus providing two intercommunicating but functionally divided treating sections within a single tank. A floor 5 under the hood divides the space thereunder into a mixing zone and a pressure chamber. Slurry passes from the pressure chamber into the relatively quiescent, clarification section of the basin and also, and ordinarily a major part of 10 the flow, returns directly into the mixing chamber. An important feature of my invention lies in the valve means by which the relative width of the flow passage from the pressure chamber back into the mixing chamber can readily be 15 varied to control the time taken for liquid entering to be treated to pass from the inlet to the pressure zone, i. e. pass through the mixing zone.

A broader aspect of my invention, but insofar as apparatus is concerned a simpler one, relates 20 to the more efficient mixing of a reagent in water. The invention is applicable to any such mixing but for purposes of exemplification will be described in connection with the flocculation of impurities in a water treating plant by the addition of a coagulant such as alum. It is generally assumed in the art that flocculation, or coagulation, requires a period of gentle stirring of the water in order to provide for thorough mixing of the reagent throughout the water and for repeated collisions between the small, newly 25 formed precipitate, or coagulum. In small flows this is a rather simple procedure. However in large flows of water, such as in a plant adapted for 30 treating millions of gallons per day, the process requires considerable apparatus and a basin of large size in order to provide for mixing over a prolonged period. This is due to the fact that the stirring must be gentle, as any turbulence tends to break up the newly formed particles. 35 However, it is difficult to mix a small amount of chemical with a large flow of water without turbulence, but turbulence is destructive to flocs. To overcome this difficulty, it is customary to rapidly and turbulent mix the reagent and water in a rapid mixing chamber, and then flocculate the precipitate in a large basin provided with 40 gentle agitation means. Thus the basin used for flocculation, or coagulation, of liquids must usually be quite large and must also be provided with baffles or other expensive structure which 45 prevents short circuiting from inlet to outlet. However, by the use of the invention herein described I am enabled to thoroughly flocculate impurities in a flow of one million gallons per day in a basin about 5½ feet long, 8½ feet wide and 55 4½ feet deep, and to completely eliminate the rapid mixing step.

The various aspects of my invention will be readily understood from a detailed consideration of the drawings in which:

Figure 1 is a longitudinal cross-sectional view of a flocculation or coagulation chamber of one aspect of the invention, with motor removed, taken along the vertical planes indicated by the line 1—1 of Figure 3;

Figure 2 is a plan view of the apparatus shown in Figure 1;

Figure 3 is a transverse cross-sectional view of the apparatus shown in Figures 1 and 2;

Figure 4 represents a plan view of a preferred embodiment of my invention when applied to a slurry type liquid treating apparatus;

Figure 5 is a transverse, vertical cross-sectional view of the apparatus taken at the vertical plane indicated by the line 5—5 on Figure 4;

5

Figure 6 is a transverse, vertical cross-sectional view of the apparatus taken at the vertical plane indicated by the line 6—6 on Figure 4;

Figure 7 is a horizontal, cross-sectional view of the apparatus taken at the horizontal planes indicated by the line 7—7 of Figure 6;

Figure 8 is a longitudinal cross-sectional view of the apparatus taken along the central axis, indicated by the line 8—8 in Figure 4.

Figure 9 is an enlarged view of a preferred type of liquid impeller particularly adapted for use in apparatus of this kind.

Referring first to the simple mixing apparatus shown in Figures 1 to 3, inclusive, I show a device eminently fitted for flocculation, or coagulation, of impurities in liquid. The apparatus comprises a relatively small basin 10 having side walls 11 and 12, ends 13 and 14 and a floor 15.

Along the side walls 11 and 12 are sharply sloping fills 16, which fill the corners so as to prevent deposit of solids therein. Likewise, longitudinally arranged along the center line of the floor is a triangular shaped fill 17 which is adapted to prevent deposit of solids along the center line of the floor. As indicated above, a 20 flocculation basin of this type can be approximately 5½ feet long, 8½ feet wide and about 5 feet deep, for flocculating about one million gallons of water per day.

A diaphragm, or false floor, 20 is placed adjacent the top of the basin 10. In the size just mentioned this diaphragm would be about 4½ feet above the floor 15. This diaphragm, or partition, can be substantially horizontal, but ordinarily it slopes slightly toward the side walls 11 and 12, as shown, in order to avoid deposit of solids thereon. This partition divides the tank into a lower reaction zone B and a superposed pressure zone A. The diaphragm 20 terminates short of the side walls 11 and 12 to leave a flow passage 21 along the side walls, as shown. A plurality of vertical baffles 22, perpendicular to the respective walls, are placed along the flow passages 21 in order to direct flows through the 25 passages 21 in a direction perpendicular to the axis of the tank. Associated with each passage-way 21 is a valve plate 23, shown in the figures as resting upon the upper side of the diaphragm 20. The valve plate 23 is pivoted at a central point 24, as shown, and is positioned by any suitable means, such as bell crank 25 actuated by rod 26. It is obvious that as the valve plates 23 are pivoted on their pivot points 24 they change the shape of the orifices 21 from a trapezoid with the large end adjacent one end wall, such as 13, to a trapezoid with the larger end at the opposite end wall of the basin. This changing in the shape of the orifice is important in my invention as it permits regulation of circulation in the device to vary the length of time required for incoming water to be treated to pass through the lower zone, as will more fully be explained hereafter.

Also associated with the diaphragm 20 is a rotor casing 27 located as near one end of the basin as possible. This rotor casing is in effect in an inverted truncated conical conduit, as shown in enlarged detail in Figure 9. Operating within the rotor casing is a rotor 30 which is shown in detail in Figure 9. As there shown, the rotor preferably comprises a vertical shaft 31 to which is fixed a perpendicular plate 32 having a diameter substantially less than the major diameter of the rotor casing, as shown. On the underside of the plate 32 are affixed a plurality

6

(usually 12 or more) of impelling blades 33 which extend radially beyond the edge of the plate 32 to adjacent the wall of the rotor casing. A rotor of this type provides for the non-turbulent pumping of a considerable volume of liquid at low head from the mixing chamber B into the pressure chamber A. Specifically, I have found it desirable in some instances to recirculate through a flocculation basin of this type about five times the normal throughput, or approximately 3500 gallons per minute. With a rotor of this type such pumping can be secured by a motor of relatively small size.

Water to be treated enters through a raw water conduit 40 which branches into two discharge outlets 41, one discharging on each side of the center line of the apparatus and in a direction perpendicular to the longitudinal axis. Chemical inlets 42 introduce suitable treating reagent to the entering liquid to be treated. Treated water is withdrawn through an outlet pipe 43 which is shown in these figures as leading from the lower section of the basin 10, adjacent the rotor. It can be mentioned that the location of the outlet 43 is not critical, for it can also be above the separating diaphragm 20 adjacent either end of the pressure zone. Location of the inlet for water and chemical is rather critical as it should be positioned as close to the end wall opposite the 30 rotor as is possible, for the reasons hereafter explained.

During operation a lower reaction, or mixing, zone of the basin contains two functionally, separate, parallel and tangential cylindrical bodies of water having a spiraling motion from the inlet end of the basin to the opposite end at which the rotor is located, as indicated by the arrows in Figures 1 and 3, although there is no structure to separate the two bodies. It will be noted that the raw water is preferably introduced at one end of the lower reaction chamber B in a direction tangential to the cylindrical bodies of water. As indicated above it will customarily be desired to recirculate liquid undergoing treatment through the basin a number of times and I have found that for many waters a recirculation of about five times is desirable. Thus the rotor 30, driven by any suitable means not shown, pumps a large volume of liquid from the lower reaction, or flocculation, chamber into the upper pressure chamber A. The major portion of this pumped liquid returns to the lower chamber through the side passageways 21 and the flow therethrough discharges at the periphery of the cylindrical bodies 35 of water in a direction tangential thereto. In this connection I usually prefer the velocity of discharge through the orifices 21 to be about 3 feet per second, which supplies sufficient energy to maintain the spiraling rotation of the liquid 50 in the lower agitation chamber from the inlet to the rotor end of the basin.

It will be noted that adjustment of the valve plates will not change the cross-sectional area of the orifices 21 but it will change the shapes of those orifices, and by changing the shape of the orifice I can vary the total time required for the entering liquid to be treated to pass through the mixing zone to and through the rotor 30. This can perhaps be more readily understood if 55 we divide the basin into five imaginary one foot sections, the section adjacent the inlet 41 being considered the first section. Assume that the valve plates are so positioned that the orifice 21 is rectangular. In that situation the cross-sectional area of the orifice for each section is

the same and equal quantities of water from the upper chamber will be discharged therethrough. Assuming a recirculation of five volumes, it is obvious that there will be about two volumes of water in the first section—one newly entering water to be treated and one volume recirculating. Actually, in one plant of the size mentioned, it takes these two volumes of water (in the size of apparatus and of the flows above mentioned) approximately ten seconds to pass through the first section. In the second section an additional volume of recirculated water is introduced through the tangential orifice 21 so that the total detention time in this section is reduced, and so on down to the last section. Actually in this plant, the detention time in the last section was 3 seconds, and the total detention time in one pass through the mixing chamber was 30½ seconds. Now assume that the valve plate 23 is set so that the wide end of the trapezoidal orifice is adjacent the rotor and the small end is at the inlet end of the chamber. Now the volume of inflowing water remains the same but the volume of recirculated material in the first section is substantially smaller (as the orifice is smaller) which means that the total retention time in this section is considerably increased—actually to about 16 seconds. In this instance the total detention time in the lower mixing zone is about 44½ seconds, for in each instance we have six volumes passing through the last section (and rotor) so the detention time in the final section is always the same. However, when the small end of the orifice is adjacent the inlet to the mixing chamber, the detention time in the first section is larger, and decreases at an even rate down to the final section—giving a greater total detention time. Now if we reverse valve plate 23 and make the wide end of the trapezoidal opening adjacent the inlet we find the largest portion of recirculated material introduced with the raw water and the total detention time in the first section is very materially decreased. Obviously the detention time in each section must also decrease so that the total detention time with this setting of the orifice plate 23 is only about half that at the other extreme, namely approximately 23 seconds. Thus it is obvious that by changing the position of the valve plate 23 the circulation of material from the top section to the lower section may be varied as desired to either deliver equal quantities along the side of the rotating cylindrical bodies of liquid in the lower section, or the major amount of so recirculated suspension may be delivered at either end of the basin to fix the actual detention time as desired. It is also obvious that with the introduction of the raw water tangentially and at one end of each cylindrically spiraling body of water there can be little or no diffusion axially, so that there is no possible by-passing or short circuiting of the entering raw water to the rotor 30. Thus I am enabled to very accurately fix and maintain the total detention time of the raw water in the reaction chamber B.

It might seem at first glance that the total detention time would be insufficient to secure complete or satisfactory flocculation, recirculating five units as above mentioned. However, I have found this amount satisfactory. This is due to the fact that by maintaining the spiraling flows above described the incoming raw water and coagulant are very thoroughly and rapidly mixed with the recirculated water containing previously formed floc, although velocities

at any particular point are kept below those at which velocities would become destructive to floc. This circulation also provides for a maximum number of collisions between particles thereby producing a very efficient flocculation. Therefore, the relative size of this device can be smaller than heretofore thought necessary for such basins, as in my structures I am enabled to recirculate a well flocculated liquid, without danger of short circuiting the entering raw water through the mixing chamber. Also, the usual flash mixer can be eliminated as dosing and thorough mixing are combined with the usually separate flocculation step, and all three take place in the one apparatus.

Figures 4 to 8, inclusive, illustrate my invention when applied to a slurry type liquid treating apparatus. In small sizes the inlet would be at one end and the rotor at the other, as shown in the preceding figures, but for purposes of illustration I show a larger size with rotors at each end and the inlet in the middle. Such a construction functionally divides the treating chamber at the center into two end sections. The apparatus shown in these figures illustrates a complete water treatment plant in which the water is first treated with a slurry in a reaction zone B, then pumped into a pressure zone A, from which latter zone a portion of the slurry is discharged into a clarification chamber C in which clear water is separated out of the circulating slurry. The three chambers will be described in detail hereafter. For the present, however, it suffices to note that the pressure chamber A is structurally divided by the raw water inlet well 101 into two sections A' and A'', as shown in Figure 8. The reaction zone B is not divided structurally, but functionally it is divided into two sections B' and B'' (Figure 8) by the water discharged at the inlet well—one-half of the inflow going toward one end and the other half to the other end. Thus, functionally, the liquid is introduced into one end of a longitudinal reaction zone B and passed spirally to the other end, from which it is pumped into the pressure chamber A. For purposes of simplification, the flow in my apparatus will be described in relation to one of the functionally separate mixing zones of Figure 8, and it will be understood that the flow in the other half will be the same except that it is in the opposite direction.

As shown in the drawing, the apparatus of my invention includes a rectangular tank 10a enclosed within side walls 11a and 12a, end walls 13a and 14a, and floor 15a. Preferably the upper portion of the side walls 11a and 12a will be vertical as shown at 50, and an intermediate portion will slope inwardly as shown at 51. In apparatus of this type it is essential that the hood, to be described hereafter, approach the side wall, and it is obvious that if both the hood and the lower side walls slope toward each other the tank can be much more shallow than if the side walls were vertical from top to bottom. Further, the additional volume resulting from vertical side walls is of no particular importance so that the design shown in Figures 5 and 6 is preferred. Below the hood, the lower side walls should be vertical, as indicated at 52. Adjacent the upper edges of the side walls 11a and 12a are launders 53 which connect to outlet pipes 54. The weir edges 55 of the launders 53 obviously should be of the same elevation, as they establish the liquid level in the tank 10a. I prefer to combine the drain and sludge concentrator into a single withdrawal

pipe 56 which is enclosed within the center fill 11a extending along the longitudinal axis of the floor. The outlet pipe 56 is provided with a plurality of short horizontally extending orifice pipes 57, as is shown in Figures 5 and 6 particularly.

A hood structure 60 extends lengthwise in the lower portion of the basin. This structure can be made in any suitable manner but for purposes of illustration is shown as comprising sloping plates 61 and 62 extending from adjacent the lower edge of the sloping side walls 51, inwardly and upwardly to adjacent the center of the tank. Preferably the lower edges of the plates 61 and 62 are provided with short skirts 63 and 64, respectively. The skirts and sloping hood are spaced a short distance from their respective side walls so as to provide passageways 65 and 66 from the space above to the space below the hood. The entire hood structure may be supported in any suitable manner in the basin, such as by gusset plates 67. At the top edges of the sloping plates 61 and 62 are vertical plates 68 and 69, respectively, which extend upwardly therefrom and terminate at a level below that of the weirs 55. These vertical plates form an inner passageway 70 which extends upwardly from the upper portion of the hood 60 and discharges adjacent but below the liquid surface as established by the weirs. Associated with the inner plates 68 and 69 are outer plates 71 and 72, respectively, which extend from above the liquid surface down to an elevation approximately that of the top of the hood 60, thereby forming outer flow passages 73 leading downwardly from the top of the inner passageway 70 and discharging downwardly over the top of the hood 60.

Within the hood 60 is placed a partition, or dividing floor, 80 which divides the space under the hood into pressure chambers A (A' and A'') above the partition and mixing chambers B (B' and B'') below it. Circular openings 81 and 81a are located in the dividing floor, one adjacent each end wall 14a and 13a, respectively. Associated with the openings are the truncated rotor casings 27, which form short conduits or passageways between the reaction, or flocculation, chambers B and the pressure chambers A. Operating within the rotor casings are rotors 30, previously described. Rotation of the rotors 30, which is secured by any suitable means such as motors 93, provides pumping of a large volume of liquid from the mixing chambers B into the pressure chambers A at a relatively low head and velocity.

The upper portions of the pressure chambers A are in open communication with the inner passageway 70. It is preferred that a valving member, or plate, 82 be associated with the passageway 70, and so constructed and arranged as to permit variable settings from one end of the pressure chambers A to the other. A suitable valving member 82 is a rectangular plate suspended on tie rods 83 which are vertically adjustable by any suitable means, not shown.

The floor 80 of the pressure chambers A terminates short of the side walls 61 and 62 of the hood (as shown in Figures 5 and 6) thereby providing outlets 84 and 85 at each side of the pressure chamber, both of which discharge into the mixing and reaction chambers B. Preferably a plurality of transverse baffles 86 are associated with these outlets 84 and 85 in order to discharge liquid from the pressure chambers A into the mixing chambers B tangentially to the rolling, 75

or spiraling, body of liquid in the mixing zone. Associated with the outlets 84 and 85 are valving plates 87 and 88, respectively. These valving plates 87 and 88, as shown particularly in Figure 7, preferably extend from one hand of each pressure chamber to the other. Each valve plate is pivoted at any suitable point, such as 89, and is moved in a horizontal plane about its pivot point by any suitable means such as bell cranks 90 actuated by a rod 91. It is desired that valve plates 87 and 88 be adjustable to provide outlets of varying width, and preferably outlets with a trapezoidal opening, varying linearly from one end of the chambers to the other, as described in connection with the first form of my apparatus.

In the form of apparatus shown in Figures 4 to 8 the liquid to be treated enters through an inlet pipe 100 which discharges into an inlet well 101 at the center of the tank. The inlet well 101 is formed between walls 102 and 103 which extend upwardly from the partition, or false, floor 80 of the pressure chambers A to above the liquid level in the basin. The inlet well 101 preferably has two outlets 104 and 105 discharging adjacent the plates 61 and 62, respectively. It will be understood that approximately half of the flow through each outlet will go into the inlet end of the functionally separate mixing zones B' and B''. A deflecting baffle 106 divides the flow from the conduit 100, so that approximately half of the flow goes through each of the passageways 104 and 105.

The necessary treating chemical can be introduced at any desired point, such as through chemical feed line 110 discharging into the influent pipe 100 (Figure 7), or through chemical feed line 111 discharging into the inlet well 101 (Figure 8), or feed lines such as 112 discharging into the pressure chamber A adjacent the rotors 30 or feed lines such as 113 discharging into the mixing chambers B (Figure 8). As is well known by those skilled in the art, the place of introduction of the treating reagent is often important and is determined by the nature of the liquid to be treated, the type of treatment desired, and the nature of the reaction between the treating reagent and the liquid. Thus, in the clarification of a turbid water by a coagulant, such as alum, the chemical is often added to the water before introduction into the treating basin, such as through chemical feed line 110 discharging into the influent pipe 100. In a softening reaction it often is preferred that the reagent, such as lime, be added in the mixing chambers B.

During operation the mixing chambers B, pressure chambers A, the passageways 84 and 85, and the lower portion of the outer clarification chambers C are filled with a slurry of liquid undergoing treatment and suspended solids collected and accumulated from previously treated liquid. As indicated above the operation for each half of the apparatus is the same, so, in order to simplify description of operation, I shall consider one-half only (say the left end of Figure 8) and describe my invention accordingly. It will be understood that the mixing zone of my large apparatus is divided functionally by the inlet well, so that, functionally, the single basin contains two units and operation is the same in both.

The operation of the rotor 30 causes slurry to be pumped from the mixing chamber B' into one end of the pressure chamber A'. A portion of the slurry entering the pressure chamber A' passes through the passageways 70 and 73 and is discharged over the hood 60 in the clarification

11

chambers C. Such discharge is controlled by the positioning of valve plate 82 and can be made, by proper adjustment of this valve, to provide for a uniform discharge throughout the length of the basin. In most instances a much greater proportion of the flow from the pressure chamber A' will be discharged through the lateral outlets 84 and 85 along the underside of the hood 60. Such discharge, preferably at a velocity of about three feet per second, imparts a rolling motion to the liquid in the mixing chamber B', as indicated by the arrows in Figures 5 and 6. Slurry is pumped only from one end of the reaction chamber B' into the pressure chamber A' and is introduced tangentially into the reaction zone B' throughout its entire length, on both sides thereof. Such introduction into, and withdrawal from, the mixing chamber B', establishes two parallel spiraling, or rolling, bodies of liquid therein which bodies extend from one end to the other. Liquid to be treated is introduced through inlet well 101 likewise discharging under the hood tangentially to the rolling bodies of slurry therein, thus assisting and maintaining the rolling motion under the hood. As water to be treated is introduced at one end and the slurry withdrawn from the other, my apparatus provides maximum detention of the water being treated in the horizontally rolling spirals and eliminates the possibility of an inadequate detention in the slurry. While it is possible for liquid undergoing treatment to pass directly through the high pressure chamber A', the passageways 70 and 73, and into the clarification space C, it is impossible for the liquid entering to be treated to be short circuited in its passage through the mixing chamber B'. I have discovered that detention time in the mixing zone is a most critical element in slurry treatment, and my apparatus is designed to prevent short circuiting in this critical phase of such processes. Thus the introduction of the slurry into the mixing chamber in a manner to establish a rolling spiral throughout the length of the mixing chamber and the introduction of liquid to be treated at one end of this rolling body of slurry and withdrawal of slurry from the opposite end of the spiral, is important to my process. Due to the fact that slurry is returned from the pressure chamber A' to the mixing chamber B' tangentially throughout the length of the apparatus, it is impossible for entering liquids to be short circuited from the inlet well 101 to the respective rotor.

It will be obvious, also, that the setting of the valve plates 81 and 88, which are associated with the outlets 84 and 85, affect the length of retention in the chamber. These valve plates may be set so as to provide a triangular opening with its greatest width at the far end (remote from rotor 30) of the pressure chamber A'. They can also be set so as to provide a uniform flow from the pressure chamber to the mixing chamber throughout the length of the basin, the wider setting at the far end of the chamber being such as to just overcome loss of head from friction and other causes in the pressure chamber A'. In those instances where maximum detention is desired the opening will be at maximum width adjacent the rotor.

An understanding of these things will probably be simplified by reference to a particular water treating plant designed to treat 10 volumes of water per minute. As the flow and treatment is equally divided on the two sides of the transverse center line (6-6 of Figure 4) half of the input,

12

or 5 units, is treated in each end. For purposes of simplification we will consider only such 5 units in either end portion. In this particular plant the rotor 30 was designed to pump 45 units per minute of water from the reaction zone B' into the pressure chamber A', or nine times the input. Three times the throughput, or 15 units per minute, were passed from the pressure chamber A' into the clarification chamber C, of which 5 units were discharged into the launder 53 and 10 units were returned into the mixing chamber B' through the passageways 65 and 66. Thirty units of slurry per minute were returned directly from the pressure chamber A' into the mixing chamber B' through the passageways 84 and 85. In order to illustrate the operation of my apparatus one can imagine the mixing chamber divided into 5 longitudinal sections, Nos. 1 to 5, with section 1 being the section adjacent the inlet end and section 5 being adjacent the rotor. In the specific example discussed, the volume of the reaction zone A' was 100 units, or 20 units per section, or four times the throughput flow per minute.

Example A

In this instance the width of the passageways 84 and 85 was such as to return a minimum amount at the inlet end (section 1) and a maximum amount at the end adjacent the rotor (section 5). The total detention time in the mixing chamber in this instance was 5.47 minutes, and is shown as follows (figures being for each imaginary section):

Sections	1	2	3	4	5
Returned from clarification zone C to mixing zone B'	2	2	2	2	2
Recirculated from pressure zone A' to mixing zone B'	2	4	6	8	10
Total volume through each section (including input)	9	15	23	33	45
Detention time in each section (minutes)	2.22	1.33	.87	.61	.44
Total detention time, minutes					5.47

Example B

The valve plates 81 and 88 were set so as to provide a uniform distribution throughout the length of the pressure chamber A' and the reaction chamber B'. The total detention time in this instance was 4.16 minutes, as follows:

Sections	1	2	3	4	5
Returned from clarification zone C to mixing zone B'	2	2	2	2	2
Recirculated from pressure zone A' to mixing zone B'	6	6	6	6	6
Total volume through each section (including input)	13	21	29	37	45
Detention time in each section (minutes)	1.54	.95	.69	.54	.44
Total detention time, minutes					4.16

Example C

In this instance the plates were set to provide for minimum discharge adjacent the impeller and a maximum discharge at the inlet end of the mixing chamber. The total detention time

in the mixing zone with this setting was 3.42 minutes, as follows:

Section	1	2	3	4	5
Returned from clarification zone C to mixing zone B'	2	2	2	2	2
Recirculated from pressure zone A' to mixing zone B'	10	8	6	4	2
Total volume through each section (including input)	17	27	35	41	45
Detention time in each section (minutes)	1.18	.74	.57	.49	.44
Total detention time, minutes			3.42		

Thus adjustment of the valve plates varies the detention time by 50% of the minimum time —without possibility of short circuiting in the mixing zone. It is important to note that the hydraulic mixing secured in the mixing chamber permits one to control the detention time of the liquid undergoing treatment, and also to bring the minimum detention time closer to the average, or desired, detention time.

The rolling motion in the mixing chamber, heretofore described, causes the heavier particles in the slurry settling on the floor to collect along the longitudinal ridge 17a. Thus the solids are automatically concentrated along the ridge 17a and are withdrawn through the outlet 56 as desired.

It will be obvious that the apparatus of my invention can take many forms. For example, in some flocculation processes the use of a reagent is not necessary, and it will be obvious that in such cases the chemical inlets can be eliminated. It is also obvious that the form of the pressure chamber can vary over a considerable variety of forms, and that the valve plates 87 and 88 can be operated in a variety of manners to secure the desired results. Such things will be understood by those skilled in the art, and need not be shown in detail.

I claim:

1. A coagulating device comprising a tank, partition means dividing said tank into a lower reaction chamber in the lower portion of said tank and a superposed pressure chamber, said partition means being so constructed and arranged as to provide open passageways between said chambers at the side of said tank, inlet means for introducing liquid to be treated and any treating reagent into one end of the reaction chamber, an outlet from the horizontally opposed end of the reaction chamber discharging into the pressure chamber, a pumping means positioned to pump liquid through said outlet, and outlet means for coagulated liquid functionally remote from said inlet means, said passageways discharging tangentially to the flow from said liquid inlet to said outlet from the reaction chamber.

2. Liquid treating apparatus comprising an elongated tank, a treated liquid outlet from the upper part of said tank, means for introducing a treating reagent to the liquid to be treated at a point functionally remote from said treated liquid outlet, a solids outlet from the lower portion of said tank, a partition structure within said tank forming therein a longitudinally extending hood in the lower portion thereof, a partition inside the hood and dividing the space under the hood into an upper pressure chamber and a lower mixing chamber, said chambers extending the length of the hood, valved conduit means leading from the pressure chamber and

discharging downwardly over the upper side of the hood, and passageways opening from the pressure chamber into the mixing chamber and located inside and adjacent the sides of the hood throughout the length thereof, characterized by flow passages leading from the mixing chamber to the pressure chamber at each end thereof, mechanically driven liquid moving members so positioned as to pump liquid through each of 10 said flow passages from the mixing chamber into the pressure chamber, an inlet for liquid to be treated discharging transversely into the mixing chamber at a point approximately midway between said flow passages, and a valve plate for each passageway, said valve plates being pivoted with respect to said passageways in such manner as to provide trapezoidal openings of variable width through said passageways.

3. Liquid treating apparatus comprising a 20 basin, partition means forming a longitudinally extending mixing chamber in the lower portion of said basin and a superposed pressure chamber, an outlet leading from said pressure chamber and discharging downwardly over the partition means, an inlet into said pressure chamber from one end of the mixing chamber, a pumping means for pumping liquid through said inlet, a passageway leading from the pressure chamber into the mixing chamber, valve means 25 for said passageway movable to vary the shape of the opening of said passageway to provide in one position an opening of uniform width and in another position a progressively enlarged opening from one end of the passageway to the other, means for introducing liquid to be treated into 30 the end of the mixing chamber opposite said inlet to the pressure chamber, a solids outlet in the lower portion of said basin, and a treated liquid outlet in the upper portion of said basin, 40 said passageway discharging into said mixing chamber tangentially to the flow from its inlet to its outlet.

4. In a liquid treating apparatus a treating 45 chamber, a horizontally extending partition structure within said treating chamber forming 50 therein a longitudinally extending reaction chamber in the lower portion thereof, and a superposed pressure chamber, passageways from the pressure chamber into the reaction chamber discharging tangentially adjacent the sides of 55 the reaction chamber, an outlet leading from the reaction chamber to the pressure chamber at one end of the reaction chamber, a mechanically driven liquid moving member so positioned as 60 to pump liquid through said outlet from the reaction chamber into the pressure chamber, an inlet for liquid to be treated discharging into the reaction chamber at the end of said reaction chamber horizontally opposed to said outlet, an inlet for introducing a treating reagent to the 65 liquid to be treated, valve members operatively connected with said passageways and pivotably mounted, said passageways in one position of said valve members having an opening of uniform width, and in another position of said valve members having a progressively enlarged opening from one end thereof to the other, and an outlet for treated liquid functionally remote from 70 said inlets for liquid and reagent.

5. A liquid treating apparatus comprising a 75 basin, partition means forming a longitudinally extending mixing chamber in the lower portion of said basin, a superposed pressure chamber and a clarification chamber, an outlet from said pressure chamber and discharging downwardly

over the partition means, inlet means for introducing liquid to be treated into said mixing chamber, a passageway from said mixing chamber to said pressure chamber, a pumping means pumping liquid through said passageway, return passageways leading from the pressure chamber into the mixing chamber, valve plates regulating flow through said passageways, a solids outlet from the lower portion of said basin, and a treated liquid outlet in the upper portion of said clarification chamber, characterized in that said inlet means discharge into one end of said mixing chamber, and said passageway leads from the other end of the mixing chamber opposite said inlet means, and said return passageways discharge tangentially to the flow from said one end of the mixing chamber to the other end thereof, whereby a spiraling motion is set up in the liquid in said mixing chamber from said one end to the other, and in that said valve plates are pivoted at their centers, whereby inward movement of one end portion of said valve plates causes outward movement of the other end portion, such movement resulting in valve openings increasing in width from one end of 25 said passageways to the other.

6. Liquid treating apparatus comprising an elongated tank, a treated liquid outlet from the upper portion of said tank, means for introducing a treating reagent to the liquid to be treated at a point functionally remote from said treated liquid outlet, a solids outlet from the lower portion of said tank, a partition structure within said tank forming therein a longitudinally extending hood in the lower portion thereof, a partition inside the hood and dividing the space under the hood into an upper pressure chamber and a lower mixing chamber, said chambers extending the length of the hood, a passageway
